[57] CLAIM

The ornamental design for a container package for solid ink, as shown and described.

DESCRIPTION

FIG. 1 is a top plan view of a holder for a solid ink;
 FIG. 2 is a front view thereof;
 FIG. 3 is a bottom plan view thereof;
 FIG. 4 is a left side view thereof;
 FIG. 5 is a right side view thereof;
 FIG. 6 is a rear view thereof;
 FIG. 7 is a top perspective view thereof;
 FIG. 8 is a bottom perspective view thereof;
 FIG. 9 is another bottom perspective view thereof with the solid ink removed;
 FIG. 10 is a cross sectional view taken along line 10—10 of FIG. 3;
 FIG. 11 is a cross sectional view taken along line 11—11 of FIG. 3;
 FIG. 12 is a cross sectional view taken along line 12—12 of FIG. 3;
 FIG. 13 is a partial view showing the indentation in the central section of FIG. 1;

FIG. 14 is a top plan view of a second embodiment of FIG. 1;

FIG. 15 is a front view of FIG. 14;

FIG. 16 is a bottom plan view of FIG. 14;

FIG. 17 is a left side view of FIG. 14;

FIG. 18 is a right side view of FIG. 14;

FIG. 19 is a rear view of FIG. 14;

FIG. 20 is a top perspective view of FIG. 14;

FIG. 21 is a bottom perspective view of FIG. 14;

FIG. 22 is another bottom perspective view of FIG. 14 with the solid ink removed;

FIG. 23 is a cross sectional view taken along line 23—23 of FIG. 16;

FIG. 24 is a cross sectional view taken along line 24—24 of FIG. 16;

FIG. 25 is a cross-sectional view taken along line 25—25 of FIG. 16;

FIG. 26 is a partial view showing the indentation in the central section of FIG. 14;

FIG. 27 is a top plan view of a third embodiment of FIG. 1;

FIG. 28 is a front view of FIG. 27;

FIG. 29 is a bottom plan view of FIG. 27;

FIG. 30 is a left side view of FIG. 27;

FIG. 31 is a right side view of FIG. 27;

FIG. 32 is a rear view of FIG. 27;

FIG. 33 is a top perspective view of FIG. 27;

FIG. 34 is a bottom perspective view of FIG. 27;

FIG. 35 is another perspective view of FIG. 27 with the solid ink removed;

FIG. 36 is a cross sectional view taken along line 36—36 of FIG. 29;

FIG. 37 is a cross sectional view taken along line 37—37 of FIG. 29;

FIG. 38 is a partial view showing the indentation in the central section of FIG. 27;

FIG. 39 is a top plan view of a forth embodiment of FIG. 1;

FIG. 40 is a front view of FIG. 39;

FIG. 41 is a bottom plan view of FIG. 39;

FIG. 42 is a left side view of FIG. 39;

FIG. 43 is a right side view of FIG. 39;

FIG. 44 is a rear view of FIG. 39;

FIG. 45 is a top perspective view of FIG. 39;

FIG. 46 is a bottom perspective view of FIG. 39;

FIG. 47 is another bottom perspective view of FIG. 39 with the solid ink removed;

FIG. 48 is a cross sectional view taken along line 48—48 of FIG. 41;

FIG. 49 is a cross sectional view taken along line 49—49 of FIG. 41; and,

FIG. 50 is a partial view showing the indentation in the central section of FIG. 39.

The broken lines in FIGS. 8, 21, 34, and 46 are for purposes of illustration only and form no part of the claimed design.
